(57) **CLAIM**

The ornamental design for an operating panel for elevator, as shown and described.

DESCRIPTION

FIG. 1 is a perspective view of front, right and top plan side of an operating panel for elevator showing our new design of the first embodiment;

FIG. 2 is a front view thereof;

FIG. 3 is a rear view thereof;

FIG. 4 is a top plan view thereof, a bottom view is a mirror image thereof;

FIG. 5 is a right side view thereof, a left side view is a mirror image thereof;

FIG. 6 is a partially enlarged view at 6-6 in FIG. 2;

FIG. 7 is a partially enlarged view at 7-7 in FIG. 2;

FIG. 8 is an enlarged end view of cutting part at 8-8 in FIG. 6 omitting the interior mechanism;

FIG. 9 is an enlarged end view of cutting part at 9-9 in FIG. 7 omitting the interior mechanism;

FIG. 10 is a reference view of usage;

FIG. 11 is a partially enlarged reference view at 7-7 in FIG. 2 according to the second embodiment; and,

FIG. 12 is a partially enlarged reference view at 7-7 in FIG. 2 according to the third embodiment.
